MULTICIRCUIT TIMING SWITCH

Carl Ludwig Anderson, Moline, Ill., assignor to
Eagle Signal Corporation, Moline, Ill., a cor-
poration of Massachusetts

Application June 1, 1935, Serial No. 24,489
Renewed August 9, 1939

25 Claims. (Cl. 200—38)

This invention relates to multi-circuit timing switches, and more particularly to switches embodying facilities for opening or closing a plurality of circuit controllers in a preadjusted timed sequence which may be conveniently and quickly revised.

Multi-circuit timing switches heretofore available for services such as those just referred to have embodied features intricate and complicated in character and have been found to be of insufficient reliability as to accuracy of timing, unwieldy as to adjustment or setting, as well as undesirable in respects of design, bulkiness and general operation.

It is, therefore, an important object of this invention to provide a multi-circuit timing switch which is of simple, sturdy and compact design, which is flexible as to operative characteristics, durable and reliable.

Another object is to provide a multi-circuit timing switch embodying parts which may be readily rearranged so as to provide for starting the time cycle by closing a control switch and resetting the timer at the end of its completed cycle, starting the time cycle by closing a control switch and resetting the timer when the switch opens, or starting the time cycle by opening the control switch and resetting the timer when the switch is closed.

Another object is to provide such a switch in which electromagnetically controlled means may be utilized, at any desired stage of the operating cycle, for causing return to a predetermined cycle starting point of the various parts of said switch as well as of the current paths governed thereby.

In a preferred embodiment of this invention, the foregoing objects and others ancillary thereto are accomplished as follows:

A motor, acting through a train of gears, a clutch and a gear rack, effects movement of a plate in a direction opposite to that urged by a spring bias associated with said plate.

A plurality of adjustable arms each having a projection for engaging said plate but which assume, according to their preadjusted positions, a non-engaging relation with said plate as it is driven by said motor. A contact member is associated with each of said adjustable arms to open or close its respectively controlled circuit when the plate has moved to permit the arm to assume its non-engaging relationship with said plate.

Electromagnetically operable mechanism is provided for lifting the projection of said adjust-

able arms free from said plate and, at the same time, opening said clutch so as to permit said plate to return to a normal "home" or "reset" position responsive to urge of its spring bias.

Additional parts may be provided as desired to effect actuation of contacts responsive to such return movement of said plate and, still other parts may be provided to permit exceedingly accurate adjustment of said adjustable arms, whereby said contacts will be actuated at precisely the desired time.

In the accompanying drawings, like parts are designated by the same reference characters throughout the several views in which

Figure 1 is a plan view of a multi-circuit timing switch embodying this invention, showing circuit controllers and associated adjusting means for two current paths and provision for two additional pairs of circuit controllers and their respective adjusting means;

Fig. 2 is a distorted isometric view of the mechanism of the switch of Fig. 1, in which, for the sake of clarity, the various elements are shown displaced axially much further than is necessary in a physical embodiment;

Figs. 3 and 4 are fragmentary plan views of the gear train clutch mechanism of Fig. 2;

Figs. 5 to 13, inclusive, are fragmentary views of various embodiments and functional stages of the circuit controlling mechanisms of Figs. 1 and 2; and

Figs. 14 and 15 are diagrammatic representations of certain circuit controller arrangements and electrical connections therefor.

Referring to Figs. 1 and 2, the motor M comprises a stator having a coil 30 for driving the rotor disc 32, which disc, in turn, drives the pinion 34.

The crown gear 36, acting through the pinion 38, drives the gear 40. The pinion 42, acting through the gear 44, pinion 46 and gear 48, drives the wide pinion 50.

The gears 52, 52 are journaled upon the shaft 54 for rotation independently thereof, and for movement axially thereon (see also Figs. 3 and 4). The pinion 56 is carried by the shaft 54 and is situated between the gears 52, 52. The discs 58, 58 are in fixed relation with the pinion 56, and are situated in close proximity to the adjacent faces of the gears 52, 52.

The grooved hubs 60, 60 are associated with the gears 52, 52, respectively, for causing axial movement of said gears relatively to the discs 58, 58. The springs 62, 62 are so applied to said hubs as to urge movement thereof to carry the

gears 52, 52 into frictional engagement with said discs.

The gears 70 and 72 are fixed upon the shaft 14; said gear 70 meshing with the pinion 56, and said gears 70 and 72 meshing with the racks 76 and 78, respectively.

A spring 80 is so applied to shaft 14 as to tend to rotate same clockwise and thereby to move the racks 76 and 78 from left to right; the direction of rotation imparted to the rotor disc 32 by excitation of the stator coil 30 being such as to rotate gears 70 and 72 counterclockwise, and thereby move the racks 76 and 78 from right to left.

15 A reciprocating plate 82 slides freely in the ways 84, 84 (best shown in Fig. 1); the racks 76 and 78 being fixed upon the under surface of said plate. The ways 84, 84 are so positioned and the racks 76 and 78 are of such length that said racks 20 will be maintained in mesh with the gears 70 and 72 throughout intended movement of said plate 82.

Said plate 82 presents a discontinuous surface having a length extending from one to the other 25 of the ways 84, 84, and a width which terminates abruptly at the edge 86 and extends substantially parallel with its path of movement a distance preferably approximating or somewhat exceeding its intended range of movement.

30 Circuit controlling mechanism C comprises pairs of contacts for a desired number of current paths, each of which contacts is functionally associated with the plate 82. As an example of such controlling mechanism, the contacts 102, 35 104 are shown in Fig. 2, which contacts are biased by gravity toward circuit closing and circuit opening positions, respectively; which gravity bias should preferably be supplemented, as by the spring 106 shown in association with contact 104.

40 As shown, each contact is journaled upon a bar or shaft 108 and carries a downwardly projecting actuating strap 110 upon which is mounted an insulating block 112. This block, in turn, 45 has secured thereto a contact of the desired form, such as 102 or 104.

In actuating relationship with each contact, an arm 114 extends in the path of the strap 110. Each of said arms is arranged for attachment 50 of one end thereof to a hinge-like support and extends from such end substantially parallel with the path of the movement of said plate 82. A projection 116 is carried by each arm for support by engaging the upper surface of the plate 82; 55 such projections being suitably spaced intermediate the ends of said arms and at a distance from the free ends thereof somewhat in excess of lengthwise movement which may be imparted to said arms as and for a purpose which will be 60 hereinafter more fully explained.

Setting means S is provided for establishing timed relationship between functional actuation of the contacts C and movement of the plate 82; a separate and independently adjustable setting 65 device being provided for respective ones of said contacts.

In the interests of clearness of disclosure of other features, Fig. 2 shows only parts of that setting device which is associated with contact 70 104. It will be there seen that the right-hand end of the arm 114 is hinged in a slot at the lower end of the post 118, such post carrying a threaded extension (not shown) which projects through a slot 120 in the index plate 122. Post 118 may 75 be clamped, in various set positions, by means

of the thumb nut 124 and the friction block 126.

As best shown in Fig. 1, each block 126 carries a reference mark associated with a dial strip 128 marked with divisions representative of the time required for the indicated movement of the plate 5 82 by the motor M.

The plate 122 is disposed substantially parallel to the path of movement of the plate 82 and the slots 120 are so formed in said plate 122 that movement of any post 118 along its associated slot will effect corresponding lengthwise movement of the associated arm 114.

The upper or contact actuating surface 132 of each arm 114 is so formed that movement of any of said arms lengthwise thereof, as by sliding its post 118 along its slot 120, will not affect the positioning of its associated contact so long as the elevation of the free end of the arm remains unchanged.

A shaft 134 extends across and below the paths 20 of the arms 114 between their projections 116 and the free ends of said arms. Said shaft 134 carries raised portions 136 for cooperation with the under surfaces 138 of the arms 114. As indicated in Fig. 2, such raised portions may be associated with the shaft 134 by fixing thereon sleeve members 140 which are cut away in the path of associated arm 114, 114, for a portion of their circumference, as at 142.

Thus, when the shaft 134 is in one position, 30 the associated arm 114 will be permitted to swing on its hinge mounting in the post 118 so as to bring its projection 116 into the path of (and therefore into what may be termed "obstructing relationship" with) the plate 82; permitting 35 movement of its associated contact to its non-actuated position. Correspondingly, when said shaft 134 is rotated so as to bring raised portion 136 into engagement with the associated arm 114, such arm will be lifted, thereby carrying the projection 116 above the path and into what may be termed "non-obstructing" relationship with the plate 82; causing the associated contact to move to its actuated position against its bias resultant from gravity and/or the spring 106.

The under surface 138 of each of the arms 114 is substantially parallel with its contact actuating surface 132, so that, during support of any of the arms 114, either by the shaft 134 or by a raised portion 136 carried thereby, lengthwise movement of said arm due to shifting of its associated post 118 along its slot 120 will not cause functionally significant movement of its associated contact.

A guide plate 144 is mounted adjacent to the shaft 134 and has a series of slots 146, 146, etc., formed therein for guiding the arms 114 and maintaining same in alignment with the cuts 142 in the member 140.

A lever 150, pivoted at 152, carries an armature or a solenoid member 154 for response to energization of the coil 156.

A link 160, formed with a 90° twist therein at 162, connects the free end of the lever 150 to the free end of the slotted arm 164 for swinging 65 said arm in counterclockwise direction responsive to excitation of the coil 156. Said arm is fixed upon the shaft 166 and has the spring 168 applied thereto for swinging said arm in the opposite direction.

The gears 170, 172 are fixed upon the shafts 166 and 134, respectively, for transmitting to said shaft 134 such movements as may be imparted to said shaft 166 by the link 160 and by the spring 168.

An end cam 174 is fixed upon the shaft 166 and has axially effective cam faces 176, 176 at respective ends thereof, as best shown in Figs. 2, 3 and 4.

5 Clutch bars 178, 178 may be carried by tongue and grooved supports 180 as indicated in Fig. 2, or by trunnion supports 180 as indicated in Figs. 3 and 4.

10 Each of said bars has, at one end thereof, an upwardly extending slotted arm 182, situated within the groove of a respective one of the hubs 60, 60 and having, at the other end thereof, an 15 upwardly extending arm 184, the free end of which is bent over for functional engagement with a respective one of the cam faces 176 of the cam 174.

15 From the foregoing it will be evident that when the shaft 166 is moved to a certain position (as, for example, the position which it assumes during effective energization of the coil 156), the bars 178 will be so moved by the projecting portions of 20 the cam faces 176, 176 that the gears 52, 52 will be moved out of frictionally driving engagement with the discs 58, 58.

25 Correspondingly, when said shaft 166 is moved to another position (as, for example, the position to which it is moved by the spring 168 during deenergization of the coil 156), the projecting portions of the cam faces 176, 176 will be withdrawn from the paths of the bent over ends of the arms 184, thus permitting the springs 62, 62, 30 acting through the hubs 60, 60, to move the gears 52, 52 into frictionally driving engagement with the discs 58, 58.

35 For certain classes of service, as will be hereinafter more fully explained, the cam 174 should be so positioned on the shaft 166 as to disengage the gears 52, 52 from the discs 58, 58 during deenergization of the coil 156, while permitting termination of such disengagement during energization of said coil.

40 In any event, the gears 178, 172 should so connect the shafts 134, 166, and/or the cam 174 should be so fixed on shaft 166 relative to said gears, that whenever the cam 174 is positioned for causing disengagement of the clutch gears 52, 52 the raised portions 136 will be positioned by 45 the shaft 134 to cause the arms 114 to withdraw their projections 116 from the path of the plate 82.

50 Contacts, similar to the contacts 102, 104, may be mounted upon any pair of the insulating blocks 112 in relationship for accomplishing any one of several functional cycles. For example, such contacts may be so assembled that, when their associated arms 114, 114 are supported either by the shaft 134 (see Figs. 5 and 12) or by the plate 55 82 (see Fig. 6), they will be separated.

55 With such an assembly, a normal setting of the arms 114, 114 associated with said contacts would be such that, during the movement of the 60 plate 82 by the motor M, said plate will be withdrawn from support of the projection 116 associated with the closing biased contact 102 before it is withdrawn from the path of the projection 116 associated with the opening biased contact 104. With this setting, said contacts will be closed only during the time occupied by the movement of the plate 82 from the position where it is withdrawn from the first named projection 116 to the position where it is withdrawn from the 70 last named projection 116 (see Fig. 7).

75 Should it be desired to prevent closure of a pair of contacts, incidental to functional cycle of the relay mechanism, while leaving other pairs of contacts conditioned for effective opening and closing, the adjustment of the arms 114, 114 as-

sociated with such contacts may be varied from that just described, so that, during the movement of the plate 82, it will be withdrawn from the projection 116 associated with the opening biased contact 104 as soon as or prior to the time it is withdrawn from the path of the projection 116 associated with the closing biased contact 102. With this setting, the contacts will remain open, as indicated in Fig. 8, throughout the movement of the plate 82 from the point where it is withdrawn from the path of the projection 116 associated with the opening biased contact 104 to the point where it is withdrawn from the path of the projection 116 associated with the closing biased contact 102. In other words, such contacts would not close at any time during the cycle.

10 Instead of employing a contact assembly as just described, similar contacts may be so assembled that, when their associated arms 114, 114 are supported either by the shaft 134 (see Figs. 5 and 12) or by the plate 82 (see Fig. 6), such contacts will be closed.

15 With such an assembly, a normal setting adjustment of said arms 114, 114 is as indicated 25 in Fig. 8, wherein said contacts will be opened only during the time occupied by the movement of the plate 82 from the position where it is withdrawn from the path of the projection 116 associated with the opening biased contact 104 to the position where it is withdrawn from the path of the projection 116 associated with the closing biased contact 102.

20 Contacts so arranged may be correspondingly caused to remain closed throughout the operative cycle by reversing the relationship of the projections 116, 116, so that, as indicated in Fig. 7, the projection 116 associated with the closing biased contact 102 will have the support of the plate 82 withdrawn therefrom at all times 30 when the support of said plate is withdrawn from the projection 116 associated with the opening biased contact 104.

25 If it is desired that any pair of contacts shall be actuated by the plate 82 whenever said plate 45 assumes its reset position, a piece such as the finger 186, shown in Fig. 13, may be applied to a desired one of the insulating blocks 112. Said finger 186 is shown so applied to the block 112 associated with the opening biased contact 104 50 that, whenever the plate 82 is in its fully restored position, the associated contacts will be closed irrespective of whether or not the raised portion 136 moving with the shaft 134 is then presented to the arm 114 associated with the 55 closing biased contact 102.

Operation of mechanism of Fig. 2

60 In Fig. 2, the various parts are shown as positioned pursuant to a certain setting of the 60 means S, the plate 82 being shown somewhat removed from its "reset" position and the coil 156 assumed to be deenergized.

65 As a result of the deenergization of coil 156, the cam 174 is so positioned as to permit the springs 62, 62 to act through the hubs 60, 60 to move the gears 52, 52 into engagement with the discs 58, 58; and the shaft 134 is so positioned that its raised portions 136 are withdrawn from the path of their respectively associated 70 arms 114. Inasmuch as the plate 82 is positioned as indicated, its support is withdrawn from the arm 114 associated with the closing biased contact 102, while said plate continues to support the arm 114 associated with the opening 75

biased contact 104. The current path between contacts 102 and 104 is therefore closed.

If, now, the stator coil 30 of motor M is energized, said motor will act through the train of gearing to move the edge 86 of said plate 82 away from the projection 116 of the arm 114 associated with the closing biased contact 102 and toward the corresponding projection associated with the opening biased contact 104.

When, in the course of such movement, said edge 86 is withdrawn from the path of said second named projection 116, the contact 104 will be moved by gravity (supplemented by its spring 106) away from the contact 102; further downward movement of contact 102 being restrained by the co-engaging arm 114 which then rests upon the shaft 134.

Thereafter, energization of coil 156 will cause such rotation of the shafts 166 and 134, as hereinbefore more fully explained, as will cause the arms 114 to be lifted by the raised portions 136 moving with the shaft 134, and will cause the gears 52, 52 to be moved away from the discs 58, 58 through the engagement of the projecting portions of the cam faces 176, 176 of the cam 174 with the bars 178, 178. As a result, the spring 80 will rotate the shaft 74 and thereby cause the gears 70, 72, acting through the racks 76, 78, to move the plate 82 to its reset position, thus bringing the surface of said plate under the projections 116, 116 of the arms 114, 114.

At the time of the commencement of such rotation of the shaft 134, both of said arms 114, 114 were supported by said shaft, and the contacts 102, 104 were in open circuit relationship; hence, the simultaneous lifting of said contacts responsive to the rotation of said shaft will maintain them in disengaged relationship.

Upon deenergization of the coil 156, the raised portions 136, 136 moving with the shaft 134 will be withdrawn from the arms 114, 114 and said arms will move a short distance toward the surface of the plate 82, whereupon the projections 116, 116 will rest upon said plate, thereby maintaining the contacts 102, 104 in open circuit relationship.

Such deenergization of the coil 156 will also result in the rotation of cam 174 by the spring 168 so as to withdraw the projecting portions of the cam faces 176, 176 from the bars 178, 178. Such withdrawal permits said bars to rock with the axial movement of the hubs 60, 60 resulting from the urge of the springs 62, 62, and the gears 52, 52 are thus carried into engagement with the discs 58, 58. Thereafter the motor M will move the plate 82 away from its reset position at such speed as is established by the running of said motor, acting through the train of gearing hereinbefore described.

During the ensuing movement of said plate 82 from its reset position, the edge 86 of said plate will be withdrawn from the projection 116 associated with the closing biased contact 102, whereupon said contact will move to closed relationship with contact 104. Such relationship will thereafter continue until said edge 86 is withdrawn from the path of the projection 116 associated with the opening biased contact 104, as hereinbefore just described.

From the foregoing it will be evident that the time of establishment of closed circuit conditioning between the contacts 102 and 104 may be established with relation to the movement of said plate 82 by moving the setting means post 118 associated with contact 102 (see Fig. 1) to

such position that the index line marked upon its friction block 126 registers with the desired time symbol on its associated dial strip 128.

Correspondingly, the time of open circuit conditioning of said contacts, with relation to the movement of said plate 82, may be established by the setting of the friction block 126 associated with the opening biased contact 104.

In conditioning a timing switch such as that shown for a large proportion of the uses to which it is suited, it will be understood that the energization of the coil 156 may be controlled by one or more pairs of the circuit controller contacts to the end that, when the plate 82 has been moved a required distance, the energization of the coil 156 will be so altered as to cause the gears 52, 52 to be moved to open clutch position. In some instances, it may be preferable to control likewise the excitation of the motor M. In any event, it will be evident that the frictional engagement between the gears 52, 52 and the discs 58, 58 provides a safety connection whereby damage to the mechanism will be avoided even should operation of the motor M be continued indefinitely without such change in condition of the coil 156 as would permit the plate 82 to move to its reset position.

Furthermore, for meeting various service conditions, the relative positionings of the slotted arm 164, the cam 174, and the raised portions 136 moving with the shaft 134 may be so varied that the gear train clutch will be opened and the arms 114, 114 will be raised either responsive to energization or to deenergization of the coil 156, as may be desired.

Electrical connections and operation

For convenience in representation, Figs. 14 and 15 diagrammatically represent illustrative examples of connections which may be established between various parts of the relay mechanism shown in Figs. 1 to 13, inclusive. In these views, a series of cams are used to indicate the relationship exemplified by plate 82 and arms 114, with their fingers 116. These cams are shown as co-operating with associated contacts for effecting positionings thereof. In these figures, the bar actuated by spring 168 represents shaft 134, and the projections on the bar represent the projections 136 on sleeves 140. The spring 80 represents spring 80 of Fig. 2. Since the coacting relationships of the various parts have been previously described, the following explanation will, for purposes of clarity in understanding, refer only to the functioning of the chief elements.

Fig. 14

With the foregoing explanations in mind, consideration will next be given to the operation of the structure typified diagrammatically by Fig. 14.

With the circuit arrangement illustrated in Fig. 14, a momentary closure of the control circuit resets the timer and starts the timing cycle. The power source is denoted by the numerals 200 and 202. The coil 156 is connected to one side of the power source through a switch 204. The other side of the coil is connected by conductor 206 to switch 208 and from switch 208 through conductor 210 to the other side, 202, of the power source. The motor M (coil 30) is directly connected to one side, 202, of the power source, and to the other side, 200, of the power source through conductor 212, contact b, and switch 204.

Contact b represents one pair of contacts 102, 75

104 and is for energizing the timer motor during the timing cycle. It is arranged to be positioned as illustrated in Figs. 5, 7, and 12. The adjusting means S for the arm 114 for the closing biased contact member is set so its reference mark on block 126 is at the O calibration on the dial strip 128. This will cause the contact b to close, as in Fig. 7, when the raised portions 136 are withdrawn from their actuating relation with surfaces 138, even though the plate 82 is in its home or reset position, since the ways 84 are arranged to stop plate 82 in its reset position so that its edge 86 is slightly removed from the projection 116 when the adjusting means associated with the arm 114 is set at zero. The arm 114 may thus assume its unobstructed relationship and contact member 102 may assume its biased position. The adjusting means S, associated with arm 114 for the opening biased contact member, is set so its reference mark on block 126 is at the calibration on the dial strip 128 corresponding to the maximum duration of the timing cycle desired. It will be assumed for this explanation that contact d is arranged as shown at C in Fig. 2 and as illustrated in Figs. 5, 6, 7, and 13. It is evident that this contact or any of the other contacts for controlling an external circuit may be arranged to operate in any one of the several ways described heretofore.

30 The normal condition of the timer is in its "timed out" position with the plate 82 driven backward against the bias of spring 80 and with contact b open, deenergizing the motor. The static friction of the gears and shafts is large enough to maintain the plate in this position even though the motor is not energized.

40 The timer is reset by closing switch 208, energizing magnet 156, which causes the projections 116 on arms 114 to assume their non-obstructing position in respect to the plate 82, also causing the release of the frictional driving engagement between the gears 52 and the discs 58 and also causing contact b to assume the open circuit relationship, illustrated in Fig. 12. The plate 82 is then restored to its reset position by spring 80.

45 The opening of switch 208, deenergizing coil 156, initiates the timing cycle. The faces of gears 52 and discs 58 are thus restored to frictional driving engagement. The raised portions 136 are now removed from the surface 138 of arms 114, as illustrated in Fig. 6. Contact b closes, as illustrated in Fig. 7, because of its "O" setting which has been hereinbefore described. The motor coil 30, being energized through the closed contact b, drives the plate 82 away from its reset position against the bias of the spring 80.

50 During the ensuing movement of said plate 82, the edge 86 of said plate will be withdrawn from beneath the projection 116 associated with the closing biased contact 102 of d, whereupon said contact will move to closed relationship with contact 104. Such relationship will thereafter continue until said edge 86 is withdrawn from the path of the projection 116 associated with the 55 opening biased contact 104.

55 From the foregoing it will be evident that the time of establishment of closed circuit conditioning between contacts 102 and 104 may be established with relation to the movement of said plate 82 by moving the setting means post 118 associated with contact 102 to such position that the index line marked upon its friction block 126 registers with the desired time symbol on its associated dial strip 128.

75 Correspondingly, the time of open circuit con-

ditioning of said contacts, with relation to the movement of said plate 82, may be established by the setting of the friction block 126 associated with the opening biased contact 104.

Further movement of the plate 82 withdraws the edge 86 from the path of the projection 116 on the opening biased contact member of b and permits it to assume its biased position. The motor stops through the opening of the b switch. The timer is now in its normal or timed out condition and another cycle of operation may be repeated by again closing and opening switch 208.

If it is desired to reset the timer during the timing period and thus extend the timing interval, switch 208 may be closed momentarily and plate 82 will instantly return to its reset position.

Fig. 15 illustrates diagrammatically the positioning of the parts so that the timing interval occurs while the coil 156 is energized. Spring 168 is positioned to lift the contact members to their non-obstructing relation with the plate 82 as well as releasing the frictional driving engagement between gears 52 and discs 58 when the coil 156 is deenergized. A momentary closure of the switch 208 starts the timing cycle by energizing the coil 156 which remains energized by a holding circuit through contact b. When contact b opens at the end of the cycle, the coil 156 becomes deenergized and the timer immediately resets. Power failure or a momentary opening of a control circuit (illustrated by switch 214) during the time cycle will cause the timers to reset before the cycle is completed.

30 In the foregoing, I have described the functioning of one type of contact assembly associated with the relay mechanism in two different operating arrangements. It will be understood that various other functionings may be produced by other settings of the adjustment means S or by 35 using other contact assemblies with any one of those described or other arrangements of the relay mechanism, but a detailed description thereof has been cancelled upon request by the Examiner. The various contact assemblies are illustrated in Figs. 5 to 13, inclusive, in their various 40 position relationships.

45 It will of course be understood that the specific description of structure and operation set forth above may be departed from without departing from the spirit of this invention as set forth in this specification and the appended claims.

Having now described my invention, I claim:

1. In a timing switch,—pairs of circuit controlling contacts for a plurality of current paths, 55 one of the contacts of each pair biased for movement toward circuit closing position and the other contact of each pair biased for movement toward circuit opening position; a reciprocating plate having an abruptly terminating surface extending substantially parallel with its path of movement; electromagnetic controlling mechanism; arms associated in actuating relationship with the respective ones of said contacts, in operable relationship with said mechanism and in retainable relationship with said plate, each of said arms so formed and supported that it may assume obstructing relationship with movement of said plate while permitting bias urged positioning of its associated contact and may be moved by 60 said controlling mechanism to non-obstructing relationship with said plate, causing its associated contact to assume an actuated position against its bias, said plate being so formed and having such a path of movement with relation to 65

said arms that it will, when its surface is positioned in certain relationships with said arms, cause them to retain their respectively associated contacts in said actuated position, each arm having setting means associated therewith for establishing various relationships between such arm and said plate whereby actuated positioning of the associated contact will be maintained throughout correspondingly diverse portions of the movement of said plate; a motor driven gear train for moving said plate in one direction, said train operatively connected to said plate through a rack and pinion and including a clutch releasable to permit movement of said plate and a portion of said train independently of the remainder of said train; spring means urging movement of said train portion to cause movement of said plate in the opposite direction; and means responsive to said controlling mechanism for releasing said clutch.

2. In a timing switch,—pairs of circuit controlling contacts for a plurality of current paths, one of the contacts of each pair biased for movement toward circuit closing position and the other contact of each pair biased for movement toward circuit opening position; a reciprocating plate having a surface extending substantially parallel with its path of movement; electromagnetic controlling mechanism; arms associated in actuating relationship with the respective ones of said contacts, in operable relationship with said mechanism and in retainable relationship with said plate, each of said arms so formed and supported that it may assume obstructing relationship with movement of said plate while permitting bias urged positioning of its associated contact and may be moved by said controlling mechanism to non-obstructing relationship with said plate, causing its associated contact to assume an actuated position against its bias, said plate being so formed and having such a path of movement with relation to said arms that it will, when its surface is positioned in certain relationships with said arms, cause them to retain their respectively associated contacts in said actuated position, each arm having setting means associated therewith for establishing various relationships between such arm and said plate whereby actuated positioning of the associated contact will be maintained throughout correspondingly diverse portions of the movement of said plate; a motor driven gear train for moving said plate in one direction, said train operatively connected to said plate and including a clutch releasable to permit movement of said plate and a portion of said train independently of the remainder of said train; spring means urging movement of said train portion to cause movement of said plate in the opposite direction; and means responsive to said controlling mechanism for releasing said clutch.

3. In a timing switch,—pairs of circuit controlling contacts for a plurality of current paths, one of the contacts of each pair biased for movement toward circuit closing position and the other contact of each pair biased for movement toward circuit opening position; a reciprocating plate biased for movement in one direction; electromagnetic controlling mechanism; arms associated in actuating relationship with the respective ones of said contacts, in operable relationship with said mechanism and in retainable relationship with said plate, each of said arms so formed and supported that it may assume obstructing relationship with movement of said plate responsive to its bias while permitting bias urged posi-

tioning of its associated contact and may be moved by said controlling mechanism to non-obstructing relationship with said plate, causing its associated contact to assume an actuated position against its bias, said plate being so formed and having such a path of movement with relation to said arms that positioning of said plate in certain relationships with said arms will cause them to retain their respectively associated contacts in said actuated position, each arm having setting means associated therewith for establishing various relationships between such arm and said plate whereby actuated positioning of the associated contact will be maintained throughout correspondingly diverse portions of the movement of said plate; a motor driven gear train for moving said plate against its said bias and involving a clutch releasable to permit movement of said plate independent of said train; and means responsive to said controlling mechanism for releasing said clutch.

4. In a timing switch,—pairs of circuit controlling contacts for a plurality of current paths, one of the contacts of each pair biased for movement toward circuit closing position and the other contact of each pair biased for movement toward circuit opening position; a reciprocating plate biased for movement in one direction; electromagnetic controlling mechanism; arms associated in actuating relationship with the respective ones of said contacts, in operable relationship with said mechanism and in retainable relationship with said plate, each of said arms so formed and supported that it may assume obstructing relationship with movement of said plate responsive to its bias while permitting bias urged positioning of its associated contact and may be moved by said controlling mechanism to non-obstructing relationship with said plate, causing its associated contact to assume an actuated position against its bias, said plate being so formed and having such a path of movement with relation to said arms that positioning of said plate in certain relationships with said arms will cause them to retain their respectively associated contacts in said actuated position, each arm having setting means associated therewith for establishing various relationships between such arm and said plate whereby actuated positioning of the associated contact will be maintained throughout correspondingly diverse portions of the movement of said plate; a motor driven gear train for moving said plate against its said bias and involving a clutch releasable to permit movement of said plate responsive to its said bias; and means responsive to said controlling mechanism for releasing said clutch.

5. In a timing switch,—a circuit controlling contact biased for movement toward a predetermined position; a reciprocating plate biased for movement in one direction; controlling mechanism; an arm associated in actuating relationship with said contact, in operable relationship with said mechanism and in retainable relationship with said plate, said arm so formed and supported that it may assume obstructing relationship with movement of said plate responsive to its bias while permitting bias urged positioning of said contact and may be moved by said controlling mechanism to non-obstructing relationship with said plate, causing said contact to assume an actuated position against its bias, said plate being so formed and having such a path of movement with relation to said arm that positioning of said plate in a certain relationship with

5 said arm will cause said arm to retain said contact in said actuated position, said arm having setting means associated therewith for establishing various relationships between said arm and said plate whereby actuated positioning of said contact will be maintained throughout correspondingly diverse portions of the movement of said plate; a motor driven gear train for moving said plate against its said bias and involving a clutch 10 releasable to permit movement of said plate responsive to its said bias; and means responsive to said controlling mechanism for releasing said clutch.

15 6. In a timing switch,—a circuit controlling contact biased for movement toward a predetermined position; a reciprocating plate biased for movement in one direction; controlling mechanism; an arm associated in actuating relationship with said contact, in operable relationship with 20 said mechanism and in retainable relationship with said plate, said arm so formed and supported that it may assume obstructing relationship with movement of said plate responsive to its bias while permitting bias urged positioning of said 25 contact and may be moved by said controlling mechanism to non-obstructing relationship with said plate, causing said contact to assume an actuated position against its bias, said plate being so formed and having such a path of movement 30 with relation to said arm that positioning of said plate in a certain relationship with said arm will cause said arm to retain said contact in said actuated position, said arm having setting means associated therewith for establishing various 35 relationships between said arm and said plate whereby actuated positioning of said contact will be maintained throughout correspondingly diverse portions of the movement of said plate; and a motor driven gear train for moving said 40 plate against its said bias and involving a clutch releasable to permit movement of said plate responsive to its said bias.

45 7. In a timing switch,—pairs of circuit controlling contacts for a plurality of current paths, one of the contacts of each pair biased for movement toward circuit closing position and the other contact of each pair biased for movement toward circuit opening position; a movable part biased for motion in one direction in a path 50 parallel with a discontinuous surface thereof; controlling mechanism; arms associated in actuating relationship with the respective ones of said contacts, in operable relationship with said mechanism and in retainable relationship with said part, each of said arms so formed and supported that it may assume obstructing relationship with bias urged movement of said part while permitting bias urged positioning of its associated contact and may be moved by said controlling mechanism to non-obstructing relationship with said part, causing its associated contact to assume an actuated position against its bias, said part being so formed and having such a path of movement with relation to said arms 55 that positioning of said part in certain relationships with said arms will cause them to retain their respectively associated contacts in said actuated position, each arm having setting means associated therewith for establishing various relationships between such arm and said part whereby actuated positioning of the associated contact will be maintained throughout correspondingly diverse portions of the movement of said part; a motor driven gear train for moving 60 said part against its said bias and involving a clutch releasable to permit movement of said part responsive to its said bias.

5 clutch releasable to permit movement of said part responsive to its said bias.

6 8. In a timing switch,—a circuit controlling contact biased for movement toward a predetermined position; a movable part biased for motion in one direction in a path parallel with a discontinuous surface thereof; controlling mechanism; an arm associated in actuating relationship with said contact, in operable relationship with said mechanism and in retainable relationship with said part, said arm so formed and supported that it may assume obstructing relationship with movement of said part responsive to its bias while permitting bias urged positioning of said contact and may be moved by said controlling mechanism to non-obstructing relationship with said part, causing said contact to assume an actuated position against its bias, said part being so formed and having such a path of movement with relation to said arm that positioning of said part in a certain relationship with said arm will cause said arm to retain said contact in said actuated position, said arm having setting means associated therewith for establishing various relationships between said arm and said part whereby actuated positioning of said contact will be maintained throughout correspondingly diverse portions of the movement of said part; a motor driven gear train for moving said part against its said bias and involving a clutch 10 releasable to permit movement of said part responsive to its said bias; and means responsive to said controlling mechanism for releasing said clutch.

15 9. In a timing switch,—a circuit controlling contact biased for movement toward a predetermined position; a movable part biased for motion in one direction in a path parallel with a discontinuous surface thereof; controlling mechanism; an arm associated in actuating relationship with said contact, in operable relationship with said mechanism and in retainable relationship with said part, said arm so formed and supported that it may assume obstructing relationship with movement of said part responsive to its bias while permitting bias urged positioning of said contact and may be moved by said controlling mechanism to non-obstructing relationship with said part, causing said contact to assume an actuated position against its bias, said part being so formed and having such a path of movement with relation to said arm that positioning of said part in a certain relationship with said arm will cause said arm to retain said contact in said actuated position, said arm having setting means associated therewith for establishing various relationships between said arm and said part whereby actuated positioning of said contact will be maintained throughout correspondingly diverse portions of the movement of said part; and a motor driven gear train for moving said part against its said bias and involving a clutch 20 releasable to permit movement of said part responsive to its said bias.

25 10. In a timing switch, the combination of 30 circuit controllers for a plurality of current paths, each controller having independently operable circuit opening and closing members, a motor, actuating means for said members comprising an actuator biased for movement in one direction, 35 means associated with said motor for moving said actuator in the opposite direction to effect operation of said members in a predetermined sequence during the movement of said actuator by the motor, an electromagnet, mechanism con- 40 45 50 55 60 65 70 75

- trolled by said magnet for simultaneously rendering all of said parts unresponsive to said actuator, and further means responsive to said electromagnetically controlled mechanism for disassociating said motor from said actuator moving means whereby to permit biased movement of said actuator.
11. In a timing switch, the combination of circuit controllers for a plurality of current paths, each controller having independently operable circuit opening and closing members, a member having actuating relationship with said controller and biased for movement in one direction, motor driven means for moving said actuating member in the opposite direction, said driven means involving clutch mechanism for freeing said actuating member from the driving effect of said motor to permit movement thereof responsive to its said bias, and setting devices for diversely establishing times of actuation for respective controllers measured by movement of said actuating member responsive to said motor driven means.
12. In a timing switch,—the combination of circuit controllers for a plurality of current paths, each controller having independently operable circuit opening and closing members, actuating means for said members comprising a motor driven actuator, parts for rendering respective ones of said members responsive to said actuator, setting devices for establishing diverse operable relationships of respective ones of said parts with said actuator, and an electromagnetically controlled mechanism for simultaneously holding all of said parts out of line with the actuator on the return movement thereof.
13. A timing switch comprising a plurality of independently operable circuit controller members, in combination with actuating means for said members including a motor operated actuator, and setting devices for independently governing the timing and relative order of actuations of respective ones of said members, each of said devices including a part for rendering its associated member responsive to operation of said actuator.
14. In a timing switch, the combination of circuit controllers for a plurality of current paths, each controller having independently operable circuit opening and closing members, actuating means for said members comprising an actuator, means, including a motor, for effecting movement of said actuator in opposite directions, parts for rendering respective ones of said members responsive to positionings of said actuator, setting devices for independently establishing diverse operable relationships of respective ones of said parts with said actuator to render said parts and their controlled members responsive to the positionings of said actuator during the motor controlled movement thereof in a presettable sequence, mechanism for simultaneously rendering all of said parts unresponsive to said actuator, and further means responsive to said mechanism for returning said actuator to the starting position of its motor controlled movement independently of said motor.
15. In a timing switch, the combination of circuit controllers for a plurality of current paths, actuating means for said circuit controllers comprising an actuator, means, including time-controlled mechanism, for effecting movement of said actuator in one direction at a uniform rate of speed, parts for rendering respective ones of said circuit controllers responsive to positionings of said actuator during the time controlled move-
- ment thereof, mechanism for simultaneously rendering all of said parts unresponsive to said actuator, and further means associated with said last named mechanism for returning said actuator to the starting position of its time-controlled movement independently of said time-controlled mechanism.
16. In timing mechanism, the combination of time-controlled means, a movable member, means whereby the rate of movement of said movable member in one direction is controlled by said time-controlled means, means for returning said movable member after its time-controlled movement, a plurality of operable means each for operation after the lapse of a diversely pre-established period of time, means governable by movement of said movable member for controlling the instant of operation of respective ones of said operable means, said governable means being adjustable to control the operation of said operable means in a presettable sequence during the time controlled movement of said movable member.
17. A circuit timer comprising an electrically operated timing device for actuating a driving member, a driven member arranged for operative engagement with and disengagement from said driving member, a plurality of switches including a switch for interrupting the circuit of said timing device and one or more switches for controlling external circuits, means for actuating said switches including a member movable from a normal position upon driving of said driven member by said driving member, means for returning said movable member to normal position upon operative disengagement of said driving and driven members, and means for moving and holding said switches in a position non-responsive to actuation by said actuating means and for operatively disengaging said driving and driven members, said actuating means effecting opening of said interrupting switch following timed actuation of said circuit switches.
18. A circuit timer comprising an electrically operated timing device for actuating a driving member, a driven member arranged for operative engagement with and disengagement from said driving member, a plurality of switches including a switch for interrupting the circuit of said timing device and one or more switches for controlling external circuits, means for actuating said switches including a member movable from a normal position upon driving of said driven member by said driving member, means for returning said movable member to normal position upon operative disengagement of said driving and driven members, and means for controlling said driving and driven members and said switches, movable to either of two positions, in one of which said driving and driven members are in operative engagement and said switches are in position responsive to said actuating means and in the other of which said driving and driven members are in operative disengagement and said switches are held in position non-responsive to actuation by said actuating means, said actuating means effecting opening of said interrupting switch following timed actuation of said circuit switches.
19. A circuit timer comprising an electrically operated timing device for actuating a driving member, a driven member arranged for operative engagement with and disengagement from said driving member, a plurality of switches including a switch for interrupting the circuit of said tim-

ing device and one or more switches for controlling external circuits, means for actuating said switches movable from a normal position upon driving of said driven member by said driving member, spring means for returning said actuating means to normal position upon operative disengagement of said driving and driven members, means for controlling said driving and driven members and said switches, movable to either of two positions, in one of which said driving and driven members are in operative engagement and said switches are in position responsive to said actuating means and in the other of which said driving and driven members are in operative disengagement and said switches are held in position non-responsive to actuation by said actuating means, said actuating means effecting opening of said interrupting switch following timed actuation of said circuit switches, and electromagnetic means for actuating said controlling means, said interrupting switch and said timing device being in series with each other and in parallel with said electromagnetic means.

20. A switching mechanism comprising a plurality of cooperating pairs of switch elements, controlling means to control the circuit conditioning of said pairs of elements and upon actuation of said controlling means to change the circuit conditioning of at least one of said pairs, holding means to hold said elements in a position non-responsive to said controlling means and to control the circuit conditioning of said pairs while in such position, a driving means, and common means to initiate controlled actuation of said driving means and to render said holding means ineffective for holding.

21. A switching mechanism comprising a plurality of cooperating pairs of switch elements, controlling means to control the circuit conditioning of said pairs and upon actuating of said controlling means to change the circuit conditioning of at least one of said pairs, holding means to hold said elements in a position non-responsive to said controlling means and to control the circuit conditioning of said pairs while in such position, an electric motor, and common means, electromagnetically operated in at least one direction to initiate motor controlled actuation of said controlling means and to render said holding means ineffective for holding.

22. A switching mechanism comprising a plurality of cooperating pairs of switch elements, controlling means to control the circuit conditioning of said pairs and upon actuation of said controlling means to change the circuit conditioning of at least one of said pairs, said controlling means including adjustable means to vary the time from initiation of actuation thereof until the actuation effects such change of circuit conditioning, holding means to hold said elements in a position non-responsive to said controlling means and to control the circuit conditioning of said pairs while in such position, an electric motor, and common means, electromagnetically operated in one direction and spring operated in the opposite direction, to initiate motor controlled movement of said controlling means

and to render said holding means ineffective for holding.

23. A time-controlled switching mechanism comprising a plurality of cooperating pairs of switch elements, controlling means to control the circuit conditioning of said pairs and, upon actuation of said controlling means, to change the circuit conditioning of at least one of said pairs, holding means to hold said elements in a position non-responsive to said controlling means and to control the circuit conditioning of said pairs while in such position, a motor, and common means to initiate motor controlled actuation of said controlling means and to render said holding means ineffective for holding, said controlling means including relatively movable portions, one portion being adjustable to vary the time from initiation of actuation of said controlling means until the actuation effects the change of circuit conditioning and the other portion being driven by said motor and cooperating with the adjustable portion in determining the time of change of said circuit conditioning, said driven portion including spring means for return of the driven portion to an initial position from which it is driven by said motor.

24. A switching mechanism comprising a plurality of cooperating pairs of switch elements, controlling means to control the conditioning of said pairs and upon actuation of said controlling means to change the circuit conditioning of said pairs, holding means to hold said elements in a position non-responsive to said controlling means and to control the conditioning of said pairs while in such position, a motor, common means to initiate motor controlled actuation of said controlling means and to render said holding means ineffective for holding, said common means including a solenoid which upon energization renders said common means effective to produce such results, and a circuit including said solenoid and at least one of said pairs of switch elements for energizing said solenoid until change in the circuit conditioning of said one of said pairs effected by said controlling means.

25. A time-controlled switching mechanism comprising a plurality of cooperating pairs of switch elements, controlling means to control the circuit conditioning of said pairs, and, upon actuation of said controlling means, to change the circuit conditioning of at least one of said pairs, holding means to hold said elements in a position non-responsive to said controlling means and to control the conditioning of said pairs while in such position, a motor, common means to initiate motor controlled actuation of said controlling means and to render said holding means ineffective for holding, said actuation, after lapse of a predetermined time, effecting motion of said controlling means whereby said change of circuit conditioning is effected, said common means including a solenoid and opposing spring means, and a circuit including said solenoid and at least one of said pairs of switch elements for maintaining constant circuit conditioning in said solenoid until said circuit is interrupted.

CARL LUDWIG ANDERSON.
